DRAFT GEAR FOR RAILWAY VEHICLES

Heinrich Egen, Essen, Germany, assignor to
Fried. Krupp Aktiengesellschaft, Essen, Germany,
a corporation of Germany

Application May 8, 1934, Serial No. 724,478
In Germany June 8, 1933

6 Claims. (Cl. 213—8)

This invention relates to draft gear for railway vehicles and more especially to the so-called continuous draft gear.

One type of such draft gear consists of two aligned rods extending substantially the full length of the vehicle and being joined together at their inner ends by a lost motion connection by means of which rigid connection is established between the rods after limited relative movement, such relative movement being opposed by a rod spring. One or more frame springs are provided to transmit force resiliently from the draft gear to the vehicle and means are provided for transmitting force rigidly from the draft gear to the vehicle after full compression of the frame spring. Means are also provided for transmitting force from the draft gear through the rod spring after predetermined unitary movement of the two rods. The frame spring is of less strength than the rod spring and, therefore, yields before the rod spring, by reason of buffing force applied to one rod only.

An object of this invention is a draft gear of the type above described in which full compression of both the rod spring and the frame spring is effected upon the establishment of rigid connection between the draft gear and the vehicle, thus utilizing the full operating capacity of the springs.

Other objects, novel features and advantages of this invention will be apparent from the following specification and accompanying drawing, wherein:

Fig. 1 is a side view partially in section of a previously known structure;

Fig. 2 is a side view partially in section of one embodiment of the invention;

Fig. 3 is a view similar to Fig. 2 with a force applied to the draft gear in one direction, and

Fig. 4 is a view similar to Fig. 2 of another embodiment of the invention.

In the modification disclosed in Fig. 1, two rods 1 and 2 are yieldingly connected together by a rod spring 3. The rod spring 3 bears against followers 4 and 5 mounted to slide longitudinally on the ends of the rods 2 and 1 and being pressed by the rod spring 3 against abutments 6 and 7 on the rods. The followers 4 and 5 and the abutments 6 and 7 are alternately connected by draft rods 8 and 9. The stroke f^2 of the rod spring 3 is limited by an abutment pipe 10 extending from the follower 4 toward the follower 5.

The draft gear is connected to the vehicle by means of one or more frame springs 11 arranged for example on the rod 1 between followers 12 and 13 longitudinally slidable on said rod, the frame spring being of less strength than the rod spring.

These followers are pressed by the spring 11 against stops 14 and 15 on the underframe 16 of the vehicle. Upon movement of the rod 1, the followers 12 and 13 are displaced by abutments 17 and 18 provided on the rod 1, thereby compressing the frame spring 11. The stroke f^1 of the frame spring 11 is limited by an abutment pipe 19 extending from the follower 14 toward the follower 15.

Upon the simultaneous application of draft or buff forces on the rods 1 and 2, the rod spring 3 is compressed, whereas a draft or a buff force applied only to the rod 1 or the rod 2 is taken up chiefly by the frame spring 11. However, means are provided for utilizing the rod spring 3 to assist in taking up buff force applied to one rod only. A stop 20 is provided on the under frame 16 which is engageable by the follower 4 upon movement of the draft gear to the left and the distance f^3 between the stop 20 and the follower 4 in its normal position is equal to the difference between f^1 and f^2 . Thus, in the event of a buff force on the rod 1, the springs 3 and 11 will be fully compressed, by the time that the follower 15 engages the tube 19 and the ends of the rods 1 and 2 engage each other, thus rigidly connecting the draft gear to the vehicle. The full operating capacity of both springs is thus utilized in opposing the buff force applied to the rod 1.

In order, however, to similarly utilize the springs 3 and 11 in the event of a buff force on the rod 2, the arrangement must be compressed to the extent of the sum of f^1 and f^2 . These different strokes in the case of a buff force from one side and a buff force from the other side are undesirable. It is, of course, possible to equalize these strokes by limiting the stroke of the rod 2 or other means to the value f^1 . However, in such case there would arise the further disadvantage that the full operating capacity of both springs could not be utilized.

In the embodiment shown in Figs. 2 and 3, the arrangement is such that a buff force applied to either the rod 30 or the rod 31 results in full compression of both springs when rigid connection is established between the draft gear and the vehicle. In this embodiment, the rods 30 and 31 are yieldingly connected together in the same manner as in Fig. 1 by a rod spring 57. The rod spring 57 bears against spring followers 58 and 59 mounted for longitudinal movement on the ends of the rods 30 and 31. The rod spring 57 presses the followers 58 and 59 against abutments 60 and 61 on the rods 30 and 31. The followers 58 and 59 and the abutments 60 and 61

are alternately connected by draft rods 62 and 63 so that the simultaneous application of any draft force on the two rods 30 and 31 results in compression of the spring 57. The stroke f^2 of the rod spring 57 is limited by an abutment pipe 64 which extends from the follower 59 toward the follower 58. The follower 59 is spaced a distance f^3 from a stop 29 on the under frame 24.

A pair of followers 12 and 21 are mounted on the rod 30 between abutments 17 and 29 and a spring 22 is interposed between the followers. The stroke of the frame spring 22 is limited by an abutment sleeve 19 extending from the follower 12 toward the follower 21. A plate 27 is loosely mounted on the rod 30 and is engageable with the stop 23 on the under frame 24. A sleeve 25 has one end engaging the plate 27 and the other end engaging the follower 21. In suitable grooves 28 in the plate 27 are mounted two semi-circular levers 26, forked at their inner ends to straddle the rod 30 and lying in the path of the abutment 30. The follower 12 is engageable with a stop 14 on the frame 24.

When a buff force is applied to the rod 30, the mode of operation of this embodiment is similar to that of Fig. 1. However, in the case of a buff force on the rod 31, abutment 29 engages the forked ends of the levers 26 to rotate the same, thereby pushing the sleeve 25 to the left to move the follower 21 toward the follower 12. The inner ends of the lever 26 are located at a distance f^2 from the face of the plate 27 and the abutment 29 is spaced at a distance f^3 from the face of the plate 27. Thus, when the follower 29 moves into engagement with the plate 27, the sleeve 25 and follower 21 are moved toward the follower 12 a distance f^2 (see Fig. 3). Thus, upon movement of the rod 31 through the distance f^1 , both springs of the rod 31 are completely compressed and rigid relationship is established between the draft gear and vehicle as shown in Fig. 3.

In the embodiment disclosed in Fig. 4, the rod spring 32 is mounted within the frame spring 33 and bears against followers 34 and 35 to force them toward the abutments 36 and 37 on the rods 42 and 43. The rod 43 is provided with an abutment 54 engaged by a plate 46. A tube 38 surrounds the rod spring and has a flange 39 at one end engaging the outer face of the follower 34 and a flange 40 at the other end engaging the outer face of a collar extending from the abutment 37.

The inner end 41 of the rod 42 is enlarged and is provided with a flange 55 engaging the follower 35. The enlarged end 41 is also provided with a hole 65 in which is received a pin 66 extending from the inner end of the rod 43.

The frame spring 33 has one end engaging a guide sleeve 44 which rests against the face of a plate 46 mounted on the rod 43 and engaging the abutment 54.

In suitable recesses in the plate 46 are provided semi-circular levers 45 having forked ends straddling the rod 43. The plate 46 also engages a stop 47 on the under frame 48. On the left side, the frame spring 33 bears against follower 49 which bears both against a stop 50 on the frame 48 and against a flange 51 on the tube 38. A sleeve 56 surrounds the frame spring together with the plate 46, sleeve 44 and follower 49. Upon the application of buff force simultaneously to both rods 42 and 43, relative movement of the rods is opposed by the rod spring 32 through the medium of abutment 37, follower 35, follower 34 and abutment 36. Upon the application of draft

force simultaneously to rods 42 and 43 relative movement thereof is opposed by the rod spring 32 through the medium of the abutment 37, tube 38, follower 34, follower 35 and head 41. A buff force applied to the rod 43 is transmitted through the abutment 54, plate 46, follower 44, frame spring 33, follower 49 and stop 50 to the vehicle. After the pipe 38 engages the abutment 53, force is transmitted from the rod 43 through the abutment 37, follower 35, rod spring 32, follower 34, tube 38 to the stop 53. The distances f^1 , f^2 and f^3 are such that the rod and frame springs are fully compressed upon the establishment of rigid relationship between the draft gear and vehicle. On the application of a buff force on the rod 42, force is transmitted through the abutment 36, follower 34, rod spring 32, follower 35, abutment 37, tube 38, follower 49, frame spring 33, guide sleeve 44, plate 46 and stop 47 to the vehicle. The levers 45 are moved by the abutment 37 to displace the sleeve 44 to the left a distance f^2 equal to the extent of relative movement of the two rods or a stroke of the rod spring, the distance f^3 of the abutment 37 from the inner ends of the levers 45 being equal to the spacing of the tube 38 from the stop 53 and the distance f^1 being equal to the stroke of the frame spring.

In each of the modifications, the distance f^1 equals the sum of the distances f^2 and f^3 , so that upon application of buff force to one rod only rigid relation is established between the draft gear and the vehicle only upon full compression of both the rod spring and the frame spring, thus making full use of the capacities of both springs.

I claim:

1. A draft gear for vehicles comprising a frame extending longitudinally of the vehicle, a rod extending longitudinally of the frame, abutments on said rod, followers engageable with said abutments, a spring interposed between said followers, stops on said frame, one of said stops being directly engageable by one of said followers, an extensible spacing member interposed between the remaining stop and follower, means actuated by said rod on movement thereof in one direction to extend said spacing member, and means for limiting movement of said followers toward each other.

2. A draft gear for vehicles comprising a frame extending longitudinally of the vehicle, a rod extending longitudinally of the frame, abutments on said rod, followers engageable with said abutments, a spring interposed between said followers, stops on said frame, one of said stops being directly engageable by one of said followers, a two-part spacer interposed between the remaining follower and stop, means actuated by said rod on movement thereof in one direction to move one spacer part relative to the other spacer part, and means for limiting movement of said followers toward each other.

3. A draft gear for vehicles comprising a frame extending longitudinally of the vehicle, a rod extending longitudinally of the frame, abutments on said rod, followers engageable with said abutments, a spring interposed between said followers, stops on said frame, one of said stops being directly engageable by one of said followers, a two-part spacer interposed between the remaining follower and stop, arcuate levers supported by one spacer part with one of said ends engaging the other spacer part and the remaining ends in position to be engaged by one of said abutments to effect movement of the second spacer part away from the first spacer part, and means for lim-

- iting movement of the followers toward each other.
4. A draft gear for railway vehicles comprising a frame extending longitudinally of the vehicle, a first and a second rod arranged in alinement and extending longitudinally of the frame, abutments on said rods, a follower engageable with each abutment, a rod spring interposed between said followers, inter-engaging flanges on the 5 first rod and the follower on the second rod, a tube surrounding said rod spring and having a flange engaging the outer face of the second rod abutment and another flange engaging the outer face of the first rod follower, a frame spring surrounding said tube, followers engaging the ends of said frame spring, a flange on said tube engaged by one of said last-named followers, stops on said frame, one of said stops being engaged by one of said last-named followers, a spacer interposed between the other stop and the other last named follower, arcuate levers supported by said 10 spacer and having one set of ends engaging said last-named follower and the remaining set of ends engageable by the second rod abutment, an additional abutment on the second rod engageable with the outer face of said spacer, and means for establishing rigid relation between the draft gear and the frame upon full compression of both said 15 springs.
5. A draft gear for railway vehicles comprising a frame extending longitudinally of the vehicle, a first and a second rod arranged in alinement and extending longitudinally of the frame, abutments on said rods, a follower engageable with 20

each abutment, a rod spring interposed between said followers, inter-engaging flanges on the first rod and the follower on the second rod, a tube surrounding said rod spring and having a flange engaging the outer face of the second rod abutment and another flange engaging the outer face of the first rod follower, a frame spring surrounding said tube, followers engaging the ends of said frame spring, a flange on said tube engaged by one of said last-named followers, stops on said frame, one of said stops being engaged by one of said last-named followers, a spacer interposed between the other stop and the other last-named follower, means actuated by said second rod upon movement thereof in one direction to move said 25 follower away from said spacer, and an additional abutment on said second rod engageable with the outer face of said spacer, and means for establishing rigid relation between the draft gear and the frame upon full compression of both said 30 springs.

6. In a draft gear for vehicles comprising a frame extending longitudinally of the vehicle, a rod extending longitudinally of the vehicle, two stops on said frame, members engageable with 25 said stops, a spring tending to maintain said members in engagement with said stops, one of said members being expansible, means for moving the other member toward the expansible member upon movement of said rod in one direction, expanding means for said expansible member, and means on said rod engageable with said expanding means to actuate the same.

HEINRICH EGEN.
